Primary Examiner — Patricia Palasik(74) *Attorney, Agent, or Firm* — Quarles & Brady LLP; Gavin J. Milczarek-Desai(57) **CLAIM**

The ornamental design for a drill head for deep hole drilling, as shown and described.

DESCRIPTION

FIG. 1 is a front perspective view of the drill head design.

FIG. 2 is a front elevational view of the drill head design.

FIG. 3 is a rear elevational view of the drill head design.

FIG. 4 is a left side elevational view of the drill head design.

FIG. 5 is a right side elevational view of the drill head design.

FIG. 6 is a top view of the drill head design; and,

FIG. 7 is a bottom view of the drill head design.

The broken line showing on the drawing disclosure is for illustrative purposes only and forms no part of the claimed design.
